[57] CLAIM

The ornamental design for a cold storage food drawer
for a boat or the like, substantially as shown and de-
scribed.

DESCRIPTION

FIG. 1 is a top plan view of a cold storage food drawer
for a boat showing my new design;

FIG. 2 is a front elevational view thereof;

FIG. 3 is a right side elevational view thereof;

FIG. 4 is a left side elevational view thereof;

FIG. 5 is a bottom plan view thereof;

FIG. 6 is a rear elevational view of a second embodi-
ment thereof;

FIG. 7 is a cross-sectional view taken along line 7—7 of
FIG. 1 but with the flap partially open;

FIG. 8 is a third embodiment wherein the bottom front
and rear edges are horizontal;

FIG. 9 is a front elevational view of FIG. 6; and

FIG. 10 is a rear elevational view of FIG. 2.
